Attorney.

UNITED STATES PATENT OFFICE.

FRITZ SAUTER, OF BASEL, SWITZERLAND.

ELECTRIC TIME SWITCH.

Application filed March 23, 1920. Serial No. 368,114.

To all whom it may concern:

Be it known that I, FRITZ SAUTER, a citizen of the Swiss Republic, and resident of Basel, Switzerland, have invented new and useful Improvements in Electric Time Switches, of which the following is a full, clear, and exact specification.

The invention relates to electric time switches comprising a spring driven clock movement adapted at predetermined intervals of time to connect in circuit an electric motor for actuating the contact elements of the switch and for automatically winding up the driving spring of the clock movement. 10 The special feature of the improved construction of the present invention consists in the arrangement whereby the winding up of the spring barrel of the clock movement at each switching operation is effected by 15 the electric motor by means of a transmission gear wheel and a coupling member co-operating therewith, the coupling member remaining connected to the transmission gear wheel until after the spring barrel has 20 been completely wound. A control element operated by the spring barrel during the winding operation disengages the coupling member with the object of winding the spring barrel at each switching operation to 25 an extent exceeding the extent of running down until the spring is fully wound.

The invention is illustrated in the accompanying drawings, Figure 1 of which is a diagrammatic view of a construction embodying the invention, whilst Figure 2 shows the detail of a commutator, Figure 3 shows the operative connection of the clock movement with a relay switch and Figure 4 is a corresponding plan view thereof.

Referring now to the drawings it will be seen that the time switch comprises the spring barrel 1 (Figure 1) of a clock movement, of which only one driving wheel 2 is shown which is connected to a time disc 40

(Figs. 3 and 4) by means of a toothed gear not shown in Figure 1, but represented in Figure 3, to rotate said time disc. The time disc 40 of the clock movement is arranged to actuate a relay switch 3 by means of tappets 41, 42 mounted on said disc and cooperating with the movable lever 3^a of the switch 3, which is preferably provided with a known quick action throwing-in device. The axis of the switch lever 3^a carries a control lever 44 with abutting parts 45, 46 arranged so as to be respectively in the path of

movement of the tappets 41, 42. The switch 3 controls a circuit indicated at 4, 5 including a small electric motor 6 and a revolving commutator 7. The latter consists of an 60 electrically conducting rotatable disc 8 having two insulating segments 9 (Figure 2) and two contact springs 10, 11 pressing against the periphery of the disc. The contact springs 10, 11 are connected to the contacts 12, 13 of the relay switch 3, and a contact spring 14 which is in constant engagement with the conducting portion of the disc 8, is connected to one terminal of the electric motor 6. The disc 8 is located on the 70 rotatable switch spindle 15, which carries the switch contacts 16 completing the electric circuit α to be controlled. The switch spindle 15 also carries a gear wheel 17 which intermeshes with an intermediary gear wheel 75 18 in engagement with a toothed pinion 19 mounted on the electric motor shaft 20. On the spindle 21 of the intermediary gear wheel 18 a transmission wheel 22 is loosely mounted between two shaft collars, the 80 wheel 22 engaging with the transmission gear 1^a of the spring barrel. The gear 1^a also intermeshes with a toothed control pinion 23 mounted upon a rotatable screw-threaded spindle 24 which is provided with a gear 85 wheel 25 intermeshing with the driving wheel 2. The intermediate spindle 21 also carries a coupling sleeve 26 adapted to slide along the spindle by means of feather and key-way, the sleeve tending to move towards 90 the gear wheel 22 under the action of a spring 27. The sleeve 26 is provided with a coupling dog 28 which co-operates with a corresponding dog 29 on the gear wheel 22. A disengaging lever 30 extends between two 95 flanges on the sleeve 26, the free end of this lever being in engagement with the control pinion 23. A pawl mechanism 31 prevents the backward movement of the spring barrel 1.

The operation of the electric time switch above described is substantially as follows:—

At a certain time, the tappet 41 of the time disc 40 (Figure 3) actuated by the clock movement strikes against the abutting 105 part 45 of the control lever 44 to throw the switch lever 3^a to the right as shown in Figure 1. When the control circuit 4, 5 is thus closed to one side by means of the relay switch 3 under the action of the time disc 110 of the apparatus the electric motor 6 is started into operation and drives the switch

spindle 15 (Figure 1) and at the same time, by means of the coupling sleeve 26, (the dogs 28 and 29 being in engagement with one another) drives the transmission gear wheel 22 to wind the spring barrel 1. After a predetermined rotary movement of the switch spindle 15 the switch contacts 16 carried thereby have completed the switching operation, that is to say the connection or disconnection of the circuit α to be controlled. As the spring barrel 1 is wound up the control pinion 23 is moved along the relatively stationary screw-threaded spindle 24 to a predetermined extent. At the same time the commutator disc 8 will have been rotated by an amount such that the contact spring 10 previously carrying current passes on to one insulating segment 9 of the disc, the contact spring 11 however which was previously not traversed by current passing from the other insulating segment to the conducting portion of the disc 8. At the next operation of the time disc 40, when the tappet 42 (Figure 3) strikes against the end 46 of the control lever 44, the switch lever 3^a of the relay switch 3 is thrown to the other side and the circuit of the electric motor is again closed through the contact spring 11 which is now in contact with the conducting portion of the commutator disc 8, whereby the current passes in the same direction as before through the motor. The electric motor thus effects a fresh switching operation in the circuit α to be controlled and a further winding of the spring barrel takes place. This repeated winding of the spring barrel causes its spring to be further wound up on each occasion since each winding operation is designed to wind up the spring to a greater extent than it is unwound by the running down of the clock movement until finally after the spring barrel has been fully wound the control pinion

23 has moved sufficiently along its spindle to cause the disengaging lever 30 to act upon 45 the coupling sleeve 26 against the action of the spring 27 so as to effect the disengagement of the coupling whereupon the winding operation is discontinued. The position of the parts under these conditions is shown 50 for example in Figure 1. As the clock movement runs down the control pinion 23 does not rotate but on the other hand the screw-threaded spindle 24 being rotated by the driving wheel 2 the control pinion 23 again 55 slowly moves downwards and again permits the engagement of the coupling sleeve 26 for a new rewinding movement.

What I claim is:—

In a spring barrel clockwork controlled 60 electric motor driven time switch, a mechanism for automatically rewinding the spring barrel of the clockwork at each switching operation, comprising a motor driven rewinding shaft, a spring barrel rewinding 65 gear wheel mounted on the said shaft, a coupling member for coupling said gear wheel to said shaft, a rotary screw-threaded spindle, means for connecting the said spindle to the clockwork to rotate the spindle, a 70 control toothed pinion movably mounted on the said spindle and arranged to be rotated by the spring barrel during the winding operation, and interconnecting means between said control pinion and the coupling member to disengage the same when the spring barrel is fully rewound, substantially as and for the purpose described.

In witness whereof I have hereunto signed my name this third day of March, 1920, in 80 the presence of two subscribing witnesses.

FRITZ SAUTER.
